CONTROL SYSTEM

Glenn E. Stoltz, Pittsburgh, Pa., assignor to Westinghouse Electric & Manufacturing Company, East Pittsburgh, Pa., a corporation of Pennsylvania

Application February 21, 1942, Serial No. 431,886

14 Claims. (Cl. 80—35)

My invention relates, generally, to control systems and, more particularly, to systems for controlling steel strip rolling mills.

In the operation of steel strip rolling mills, it is necessary that the mill speed be reduced very considerably when the end of a new coil of strip is threaded through the mill in order to enable the strip to be properly threaded into the mill rolls. In the operation of tandem strip rolling mills, it has been the practice to slow the mill down to such a speed that the rolls of the last roll stand are rotating at the desired threading speed. Since the speeds of all of the roll stands are varied simultaneously and since the speeds of the stands ahead of the last roll stand decrease progressively toward the first roll stand, when the speed of the mill is so decreased as to produce the desired threading speed on the last roll stand, the speeds of the preceding roll stands are very low and the time required for threading the end of strip through the several roll stands is very long.

It is an object of my invention to provide a control system for a tandem strip rolling mill which shall function to so control the mill as to permit threading of the mill in a minimum length of time.

Another object of the invention is to provide a control system for a tandem strip rolling mill which shall function automatically to provide the desired threading speed for each succeeding roll stand as the end of a strip which is being threaded through the mill approaches each of the stands.

These and other objects and advantages will be apparent from the following detailed description taken in connection with the accompanying drawing, the single figure of which is a diagrammatic representation of a tandem strip rolling mill control system embodying the principal features of the invention.

In practicing the invention, a main generator 2 is connected to energize a main bus comprising conductors 4 and 6 from which the armatures of the motors 8, 10, 12, and 14 receive their energization. The motors 8, 10, 12, and 14 drive reducing roll stands 16, 18, 20, and 22 of a continuous strip rolling mill. The excitation of the main generator 2 may be varied by a variable resistor 24 driven by a motor 26 to thereby vary the speeds of the motors 8, 10, 12, and 14 simultaneously. The motor 26 is controlled by a reversing circuit control device 28, which, in turn, is controlled by load responsive relays 30, 32, and 34, and speed responsive pilot generators 36, 38, 40, and 42 under the control of a circuit control device 44.

Considering the invention more in detail, the reversing circuit control device 28 may be controlled by the selective operation of a pair of

potential responsive relays 46 and 48 through their contact elements 50 and 52, respectively. When the relay 46 is actuated and its contact element 50 is in the upper circuit closing position, an energizing circuit for the rheostat motor 26 is completed extending from positive potential through conductors 54 and 56, the contact element 50, conductors 58 and 60, the armature of the rheostat motor 26, conductors 62 and 64, the contact element 52, and conductors 66 and 68 to negative potential. When the relay 46 is released and the relay 48 is actuated, an energizing circuit of reversed polarity is completed for the rheostat motor 26 extending from positive potential through conductors 54 and 56, the contact element 52 in the upper circuit closing position, the conductor 62, the armature of the rheostat motor 26, the conductor 60, the contact element 50, and the conductors 66 and 68 to negative potential.

5 The energizing circuit for the rheostat motor 26 which is completed by the actuation of the relay 46 will cause the rheostat motor to drive the rheostat 24 in such a direction as to decrease the energization of the field winding 69 of the main generator 2 to thereby decrease the energization of and decelerate the motors 8, 10, 12, and 14. When the relay 48 is actuated, the energizing circuit for the rheostat motor 26 controlled thereby will cause the rheostat motor to actuate the rheostat 24 in such a direction as to increase the energization of the field winding 69 of the main generator 2 to thereby accelerate the motors 8, 10, 12, and 14.

10 The relays 30, 32, and 34 are potential responsive relays connected to respond to the potential drops across shunt members 70, 72, and 74 which are connected in the energizing circuits of the motors 8, 10, and 12, respectively. Time-delayed pickup relays 71, 73, and 75 are disposed to be connected in an energizing circuit by the actuation of the relays 30, 32, and 34. When the contact element 76 of the relay 71 is in the lower circuit closing position and the contact elements 40 78, 80, and 82 of the circuit control device 44 are in the left-hand position opposite to the position shown in the drawing, the pilot generator 36 will be connected to energize the relay 46 in a circuit extending from one terminal of the generator 36 through conductor 84, a resistor 85, a conductor 86, the contact element 76 of the relay 71, conductors 87 and 88, the contact element 78, a conductor 90, a variable resistor 92, a conductor 94, the winding of the relay 46, conductors 96 and 98, and a conductor 100 to the other terminal of the generator 36. The variable resistor 92 may be adjusted so that its effective resistance value will be such as to cause the relay 46 to pick up when the speed of the mill motor 8 is above the desired threading speed, and to be released when

15 20 25 30 35 40 45 50 55 60

the rheostat 24 has caused the motor 8 to be decelerated to the desired threading speed.

When the end of a strip of material 101 which is being threaded through the mill enters the roll stand 16, there will be a very considerable increase in the load current of the motor 8, and this will cause the relay 30 to pick up to, in turn, energize the relay 71. After the time delay for which the relay 71 is calibrated or adjusted, the contact element 76 of the relay 71 will be moved from the lower circuit closing position to the upper circuit closing position to disconnect the relay 46 from the pilot generator 36 and to connect the relay 46 to be energized by the pilot generator 38 in a circuit which extends from one terminal of the pilot generator 38 through a conductor 102, a resistor 103, a conductor 104, a contact element 105 of the relay 73 in the lower circuit closing position, conductors 106 and 108, the contact element 76, the conductor 88, the contact element 78, the conductor 90, the variable resistor 92, the conductor 94, the winding of the relay 46, and conductors 96, 98, and 110 to the other terminal of the pilot generator 38.

When the relay 46 is energized by the pilot generator 38, it will cause the rheostat 24 to further decrease the excitation and, therefore, the output potential of the main generator 2 to decelerate the motors 8, 10, 12, and 14 until the speed of the motor 10 has decreased to the desired threading speed, at which time the output potential of the pilot generator 38 will have been decreased to where it is insufficient to further maintain the relay 46 actuated. When the end of the strip 101 enters the roll stand 18, the additional load on the motor 10 will cause the relay 32 to pick up and, in turn, energize the relay 73. After the interval of time for which the relay 73 is calibrated or adjusted, its contact element 105 will be picked up to disconnect the relay 46 from the pilot generator 38 and connect it to be energized by the pilot generator 40 in a circuit which extends from one terminal of the generator 40 through a conductor 112, a resistor 113, a conductor 114, a contact element 115 of the relay 75, conductors 116 and 118, the contact element 105, the conductor 108, the contact element 76, the conductor 88, the contact element 78, the conductor 90, the variable resistor 92, the conductor 94, the winding of the relay 46, and conductors 96, 98, and 120 to the other terminal of the generator 40. The actuation of the relay 46 will again cause the motors 8, 10, 12, and 14 to be decelerated until the speed of the motor 12 is such as to provide the desired threading speed of the roll stand 20, at which time the decreased potential of the pilot generator 40 will permit the relay 46 to be released.

When the end of the strip 101 enters the roll stand 20, the relay 34 will pick up to energize the time delay relay 75. After the time interval for which the relay 75 is calibrated, its contact element 115 will be moved to the upper circuit closing position to connect the pilot generator 42 to energize the relay 46 in a circuit which extends from one terminal of the generator 42, a conductor 122, a resistor 123, a conductor 124, the contact element 115, the conductor 118, the contact element 105, the conductor 108, the contact element 76, the conductor 88, the contact element 78, the conductor 90, the variable resistor 92, the conductor 94, the winding of the relay 46 and conductors 96 and 98 to the other terminal of the generator 42. The relay 46 will thus pick up to cause the deceleration of the motors 8, 10, 12,

and 14 until the motor 14 is running at such a speed as to provide the desired threading speed of the reducing rolls of the roll stand 22, at which time the pilot generator 42 will no longer maintain the relay 46 actuated, and the relay 46 will be permitted to drop.

After the strip 101 has been threaded through the mill, the motors 8, 10, 12, and 14 may be accelerated to the normal running speed of the mill 10 by moving the contact elements 78, 80, and 82 of the circuit control device 44 to the right-hand position shown in the drawing. When in the circuit closing position, the contact element 82 will close an energizing circuit for the lower winding 15 of the relay 48 extending from positive potential through a conductor 125, the contact element 82, a conductor 126, a lower winding of the relay 48, a conductor 128, a calibrating resistor 130, and a conductor 132 to negative potential. The relay 20 48 will thus be actuated to cause the rheostat motor 26 to actuate the rheostat 24 in such a direction as to increase the output potential of the main generator 2 and thereby accelerate the motors 8, 10, 12, and 14. The upper winding of the relay 48 is connected to oppose the lower winding and is energized by the pilot generator 36 when the contact element 80 is moved to circuit closing position in a circuit which extends from one terminal of the generator 36, through conductors 25 84 and 86, the contact element 80, a conductor 134, a calibrating resistor 136, a conductor 138, the upper winding of the relay 48, and conductors 96, 98, and 100 to the other terminal of the generator 36. When the mill has been accelerated 30 to the desired normal running speed, the output potential of the pilot generator 36 will have increased to such a degree that its energization of the upper winding of the relay 48 will be sufficient to counteract the energization of the lower 35 winding of the relay 48 and cause this relay to be released, thus deenergizing the rheostat motor 26 and discontinuing the acceleration of the mill.

It is to be understood that the upper winding 40 of the relay 48 may be connected by the circuit control device 44 to be energized by any of the pilot generators 38, 40 and 42 instead of the generator 36 as described hereinbefore, to thereby control the speed of the mill in accordance with the speed of any desired one of the roll stands.

50 It is to be understood that limit switches or other equivalent devices which will respond to the position of the end of the strip which is being threaded through the mill, may be used in the place of the load relays 30, 32, and 34 and their 55 associated time-delayed relays 71, 73 and 75 to connect succeeding ones of the pilot generators 38, 40 and 42 to control the decelerating relay 46.

It is also to be understood that the variable 60 resistor 92 may be adjusted so as to make the relay 46 responsive to any desired threading speed at the several roll stands. It is also to be understood that the calibrating resistors 130 and 136 may be so adjusted as to cause the mill to be accelerated to any desired normal running speed. 65 The time-delayed-release relays 71, 73 and 75 may be adjusted to pick up at a sufficient interval of time after the entry of the end of the strip 101 into the roll stands with which each of these 70 relays are associated to permit the system to decelerate the mill until the next roll stand into which the end of the strip is to be threaded has been decelerated to the desired threading speed. The variable resistors 85, 103, 113, and 123 are 75 provided as calibrating resistors so that different

threading speeds may be provided at each of the roll stands.

In the operation of the system when the mill is running at normal operating speed and it is desired to thread a new strip of material through the mill, the circuit controlling device 44 may be moved to the left-hand position to thereby cause the mill to be decelerated until the desired threading speed has been reached by the first roll stand 16. At a predetermined time after the strip has entered the roll stand 16, the mill will be decelerated until the rolls of the roll stand 18 are running at the desired threading speed. At a predetermined interval after the strip has entered the roll stand 18, the mill will be decelerated until the rolls of the roll stand 20 are running at the desired threading speed. At a predetermined interval after the strip has entered the roll stand 20, the mill will be decelerated until the rolls of the roll stand 22 are rotating at the desired threading speed. With the mill thus threaded, it may be accelerated to the normal running speed by moving the circuit control device 44 to the right-hand position shown in the drawing, and the system will automatically accelerate the mill to normal running speed, as explained hereinbefore.

Thus, a considerable saving in the time required to thread a strip rolling mill is made by the system since none of the reducing rolls are decelerated below their desired threading speed until the end of the strip which is being threaded through the mill has passed through the preceding roll stand and it is necessary to decelerate the next roll stand to the desired threading speed.

Thus, it will be seen that I have provided a control system for a tandem strip rolling mill which shall function to automatically provide the desired threading speed for each succeeding roll stand as the end of a strip which is being threaded through the mill approaches each of the stands and which will thus function to permit threading of the mill in a minimum length of time.

In compliance with the requirements of the patent statutes, I have shown and described herein a preferred embodiment of my invention. It is to be understood, however, that the invention is not limited to the precise construction shown and described but is capable of modification by one skilled in the art, the embodiment herein shown being merely illustrative of the principles of my invention.

I claim as my invention:

1. In a control system for a motor driven strip rolling mill, a main generator to which the mill motors are connected for energization, and means responsive to the speeds of the successive motors and the position of the end of the strip with respect to successive roll stands for automatically controlling the potential of the generator to provide the desired threading speed at each succeeding roll stand as the end of a strip which is being threaded through the mill approaches each succeeding roll stand.

2. In a control system for the drive motors of a motor driven tandem strip rolling mill, means for varying the speed of the drive motors, and means responsive to the speed of the drive motor associated with one roll stand and the entry of the end of a strip which is being threaded through the mill into the preceding roll stand for varying the speeds of the drive motors associated with the roll stands.

3. In a control system for the drive motors of a motor driven tandem strip rolling mill, time

delayed relay means responsive to the entry of the end of a strip which is being threaded through the mill into one roll stand, means responsive to the speed of the drive motor for the next succeeding roll stand, and means responsive to said relay means and said speed responsive means for varying the speeds of the drive motors.

4. In a control system for the drive motors of a motor driven tandem strip rolling mill, time delayed relay means responsive to the entry of the end of a strip which is being threaded through the mill into one roll stand, means responsive to the speed of the drive motor for the next succeeding roll stand, and means responsive to said relay means and said speed responsive means for reducing the speeds of the drive motors sufficiently by the time the end of the strip reaches the said succeeding roll stand to provide the desired threading speed for the said succeeding roll stand.

5. In a control system for the drive motors of a motor driven tandem strip rolling mill, relay means associated with each roll stand beyond which there is a succeeding roll stand in the direction of travel of a strip which is being threaded through the mill and responsive to the entry of the strip into the associated roll stand, speed responsive means associated with each of the roll stands succeeding the first roll stand, and means responsive to each relay means and the speed responsive device associated with the succeeding roll stand for reducing the speeds of the drive motors sufficiently to provide the desired threading speed for the said succeeding roll stand.

6. In a control system for the drive motors of a motor driven tandem strip rolling mill, time delayed relay means associated with each roll stand beyond which there is a succeeding roll stand in the direction of travel of a strip which is being threaded through the mill and responsive to the entry of the strip into its associated roll stand, means responsive to the roll speed of each of the roll stands succeeding the first roll stand, and means responsive to said time delayed relay means and the speed responsive device associated with the succeeding roll stand for reducing the speeds of the drive motors sufficiently by the time the end of the strip reaches the said succeeding roll stand to provide the desired threading speed for the said succeeding roll stand.

7. In a control system for the drive motors of a tandem strip rolling mill, means for controlling the speeds of the drive motors simultaneously, means responsive to speed of the rolls of each of the roll stands, means whereby each speed responsive means controls the speed controlling means when connected for such control, means for connecting the speed responsive means associated with the first roll stand to control the speed control means, and means responsive to the entry of the end of a strip which is being threaded through the mill into each of the roll stands except the last for connecting the speed responsive means associated with the next succeeding roll stand to control the speed controlling means.

8. In a control system for the drive motors of a tandem strip rolling mill having a drive motor associated with each of its roll stands, means for accelerating the motors, means for decelerating the motors, means responsive to the speed of the rolls of the first roll stand for

actuating said decelerating means until the speed of the first roll stand has been reduced to the desired threading speed for that roll stand, means responsive to the entry of the strip into any roll stand which has a succeeding roll stand and the speed of the succeeding roll stand for actuating the mill decelerating means until the speed of the said succeeding roll stand has been reduced to the desired threading speed for that roll stand, and control means responsive to the speed of one of the roll stands for causing said accelerating means to accelerate the mill to normal running speed.

9. A control system for a tandem rolling mill having a plurality of motor-driven roll stands disposed to operate upon a strip of material, means for collectively varying the speeds of the motor-driven roll stands over a predetermined speed range between threading and normal running speeds, and electro-responsive control means operatively associated with the motor-driven roll stands for controlling the operation of the speed varying means, said electro-responsive means being operable to effect successive reductions in the speeds of the roll stands in response to the entry of the end of the strip of material into a preceding roll stand and the speed of the next succeeding roll stand, thereby to provide for progressively reducing the speeds of the roll stands during a threading operation.

10. A control system for a tandem rolling mill having a plurality of motor-driven roll stands disposed to operate upon a strip of material, a main generator to which the driving motors are connected, means for varying the voltage of the main generator to simultaneously vary the speeds of the motors, and control means jointly responsive to a predetermined increase in the load of one motor and the speed of the next succeeding motor for controlling the operation of the voltage varying means, thereby to effect successive reductions in the speeds of the roll stands as the leading end of the strip of material approaches each succeeding roll stand.

11. In a control system for the driving motors of a tandem rolling mill having a plurality of roll stands disposed to operate on a strip of material, a source of variable-voltage power for the motors, means operable to vary the voltage of the power source to simultaneously vary the speeds of the motors between threading to normal running speeds, control means associated with each roll stand operable when connected to the voltage control means to reduce the speed of its associated roll stand to a desired threading speed and to effect a corresponding reduction in the speeds of the other roll stands, manually operable means for connecting the voltage control means to the control means of the first roll stand, and additional control means associated with each roll stand except the last roll stand operable in response to the entry of the leading end of the strip into the associated roll stand to transfer the connection of the voltage control means to the next succeeding control means, thereby to provide for reducing the speeds of the roll stands to the desired threading speed at each succeeding roll stand.

12. In a control system for the driving motors of a tandem rolling mill having a plurality of roll stands disposed to operate on a strip of material, a source of variable voltage power for the motors, means for controlling the voltage of the power source to simultaneously vary the speeds of the motors, a pilot generator driven in accord-

ance with the speed of each roll stand and operable when connected to the voltage control means to cause said means to reduce the speed of all the roll driving motors a predetermined amount from their normal running speeds, switch means operable to connect the pilot generator of the first roll stand to the voltage control means to effect a predetermined reduction in the speed of the first roll stand to a desired threading speed and corresponding reductions of the speeds of the succeeding roll stands, and means associated with each roll stand except the last roll stand operable in response to the entry of the strip of material therein to connect the voltage control means to be responsive to the pilot generator of the next succeeding roll stand, thereby to effect successive reductions in the speeds of the roll stands as the end of the strip approaches each succeeding roll stand during a threading operation.

13. In a control system for the driving motors of a tandem rolling mill having a plurality of roll stands disposed to operate on a strip of material, a source of variable voltage power for the motors, means for controlling the voltage of the power source to simultaneously vary the speeds of the motors, a pilot generator driven in accordance with the speed of each roll stand and operable when connected to the voltage control means to cause said means to reduce the speed of all the roll driving motors a predetermined amount from their normal running speeds, switch means operable to connect the pilot generator of the first roll stand to the voltage control means to effect a predetermined reduction in the speed of the first roll stand to a desired threading speed and corresponding reductions of the speeds of the succeeding roll stands, and load-responsive relay means associated with each drive motor except the last drive motor operable in response to the entry of the end of the strip into its associated roll stand to transfer the connection of the voltage control means to the pilot generator of the next succeeding roll stand, thereby to effect successive reductions in the speeds of the motors as a group as the end of the strip approaches each succeeding roll stand during a threading operation.

14. In a control system for a tandem rolling mill or the like, having a plurality of roll stands disposed to operate upon a strip of material and a motor connected to drive each roll stand, a main generator for supplying variable voltage power to the motors, a motor-operated rheostat operable to vary the voltage of the main generator, relay means selectively operable to control the operation of the motor-operated rheostat, a pilot generator connected to each roll stand operable to develop a voltage in accordance with the speed of the associated roll stand, a load responsive relay connected to each drive motor except the drive motor of the last roll stand, a time-delay relay controlled by each load-responsive relay, said load-responsive relays, time-delay relays and pilot generators being electrically interconnected and connected to the relay means for controlling the operation of the motor-operated rheostat to effect a progressive reduction in the speeds of the roll stands as the leading end of the strip of material passes through the mill, whereby the desired threading speed at each roll stand is obtained before the leading end of the strip enters the rolls.

GLENN E. STOLTZ.
